TOBACCO HUMIDOR

Bernard Bayuk, Dayton, Ohio

Application July 26, 1946, Serial No. 686,299

8 Claims. (Cl. 312—31,3)

1

This invention relates to humidors for the storage of tobacco and tobacco products.

One of the principal objects of the invention is to provide a humidor wherein different types or blends of tobacco or tobacco products may be stored in a properly humidified atmosphere without loss or adulteration of aroma.

Another object is to provide a humidor having a compartment for containing a suitable source of moisture and a plurality of other compartments such as drawers for receiving tobacco or tobacco products for storage, and which is so constructed that each storage compartment has adequate access to the moisture compartment while at the same time direct circulation of air between the storage compartments is substantially prevented to minimize loss or adulteration of aroma from the tobacco.

It is also an object of the invention to provide such a multi-compartment humidor wherein the moisture compartment is readily removable as a unit to facilitate refilling or otherwise replenishing its contents without affecting the contents of the storage compartments.

A further object is to provide a humidor having multiple separate storage compartments and which may be readily made by mass production methods at low unit cost and also from materials such as plastic which will provide a pleasing and decorative general appearance.

Other objects and advantages of the invention will be apparent from the following description, the accompanying drawings, and the appended claims.

In the drawings, in which like characters of reference designate like parts throughout—

Fig. 1 is an exploded view in perspective of a humidor constructed in accordance with the invention;

Fig. 2 is a view in transverse section of the humidor shown in Fig. 1 and substantially on the line 2—2 of Fig. 1;

Fig. 3 is a fragmentary view in longitudinal section of the humidor shown in Fig. 1, the view being taken through the rear end of the cabinet and moisture compartment as indicated by the line 3—3 of Fig. 1; and

Fig. 4 is a fragmentary view in section illustrating means for securing the moisture compartment within the humidor shown in Fig. 1.

Many tobacco users like to keep on hand a variety of types or blends of tobacco or tobacco products ready for immediate use. This is particularly true of pipe smokers who either blend their own smoking mixture from selected differ-

2

ent tobaccos or smoke different tobaccos alternately, but it also applies to a considerable extent to smokers of cigars and cigarettes. The proper storage of such different tobaccos requires a humidified atmosphere to which the tobacco is freely exposed to keep it adequately moist for cool smoking. On the other hand, one of the important characteristics by which and for which different tobaccos are distinguished and used is aroma, and if two or more tobaccos or tobacco products of different characteristic aromas are stored under conditions permitting free flow of air therebetween, one or more may be subject to loss or adulteration of its aroma as a result of intermingling with those of the others.

In accordance with the present invention there is provided a humidor wherein a variety of different types or blends of tobacco or tobacco products may be simultaneously stored in a properly humidified atmosphere and which is so constructed that the aroma of each tobacco will be maintained and prevented from intermingling with other tobaccos present in the same humidor. The humidor of the invention permits ready access to any desired one of the materials stored therein without disturbing its other contents, and it also includes a moisture compartment having direct communication with each storage compartment for the proper distribution of moisture while controlling intercommunication between the storage compartments themselves to prevent loss of aroma from the contents of any particular compartment. Also this moisture compartment may be quickly and easily refilled or otherwise replenished without disturbing the contents of any of the storage compartments.

The drawing shows a preferred embodiment of the invention wherein the cabinet, indicated generally at 10, is of rectangular outline and is provided with a plurality of storage compartments in the form of drawers 11 supported one above the other by means such as cleats 12 for sliding movement into and out of the cabinet, the drawers being provided with suitable handles 13. These parts are shown as made of plastic and may be advantageously formed by molding from a suitably strong and water-proof organic plastic such as phenol formaldehyde, urea or melamine formaldehyde or a methacrylic resin such as methyl methacrylate; other materials such as stainless steel or aluminum may also be used.

Each of the drawers 11 is adapted to contain a quantity of tobacco or tobacco products such as cigars, cigarettes, pipe tobacco, or the like, as indicated diagrammatically at 15. In order to

control and substantially prevent the circulation of air between different drawers 11, such as to cause loss or adulteration of aroma from the contents thereof, the drawers may be formed to have close fit within cabinet 10, and also cleats 12 may extend the full length of the interior of the cabinet to provide a baffle further restricting the circulation of air while serving as a stop for moisture compartment 20.

In accordance with the invention a moisture compartment 20 is provided in cabinet 10 adapted to contain a supply of moisture for humidifying the contents of drawers 11. This compartment may be formed separately from cabinet 10, as illustrated in Fig. 4, and adapted for removable positioning therein to facilitate access thereto and replenishing the supply of moisture. As shown, the compartment 20 includes inner and outer walls 21 and 22, side walls 23 and a bottom 24 together defining a relatively flat chamber adapted to be filled with a quantity of moisture absorbent material 25 which will readily receive and retain a considerable supply of moisture, an example of satisfactory material being a felt of sufficient resilience to prevent undue matting or wadding within the compartment. The walls of the compartment 20 are formed in such dimensions and proportions as to extend substantially from the bottom to the top of the cabinet 10 to provide the rear wall thereof. This compartment may be held firmly in position in a variety of ways permitting ready removal, for example by friction fit, which may be facilitated by grinding or otherwise roughing the contacting surfaces of compartment walls 23 and the inside of the cabinet, or by forming these contacting walls surfaces with cooperating lugs or like projections and complementary receiving grooves as indicated at 26. With this construction, and with the parts formed of material of some resiliency as in the case of the above mentioned materials, the compartment 20 may readily be snapped out of place for rewetting of the backing therein and then snapped back into place as shown.

The invention also provides for the free transmission of moisture from compartment 20 to the contents of each of drawers 11 individually and separately without permitting direct communication or circulation of air between the drawers themselves. Each of drawers 11 is provided at its inner end with an opening for receiving moisture from the moisture compartment. As shown, this opening is provided by terminating the rear wall 30 of each drawer short of the side walls of the drawer, thus leaving openings 31 between each drawer, and the bottom of the next higher drawer or, in the case of the uppermost drawer, the top of the cabinet. The inner wall 21 of compartment 20 is provided with laterally extending slots 32 adapted to register with the openings 31. In the case of the top drawer, the opening from compartment 20 is shown as provided by terminating the inner wall 21 of the moisture compartment short of the top of the cabinet, leaving an opening 33 for moisture as shown.

This construction provides for ready transmission of moisture from the packing 25 in compartment 20 separately to the interior of each of the drawers 11, but since the drawers abut this inner wall 21 when closed, as shown in Fig. 3, direct communication from drawer to drawer is prevented. Also, with compartment 20 well filled with the absorbent packing 25, there is no appreciable tendency for the aroma of the con-

tents of any one drawer to be transmitted by way of the compartment 20 to the contents of any other drawers, and the removable construction of this compartment facilitates ready changing of packing 25 to prevent contamination of the tobacco by over long use of the same packing.

The invention thus provides a humidor wherein a variety of different tobacco and tobacco products may be stored in a properly humidified atmosphere without impairing their characteristic aromas. This humidor contains multiple storage compartments and affords ready access to each without disturbing the contents of the others. It is simple in construction but of decorative appearance, and in addition it is adapted for ready production in large quantities from easily fabricated materials and hence at low unit cost. Moreover, its structural and operational principles are such that it may be formed in varied sizes, capacities, and shapes without sacrificing its other advantages.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

30 1. A tobacco humidor of the character described comprising, in combination, a cabinet, means providing in said cabinet a plurality of separate compartments for storage, humidifying means within said cabinet, and means providing for communication from said humidifying means to each of said compartments and substantially preventing direct communication between any of said compartments.

40 2. A tobacco humidor of the character described comprising, in combination, a cabinet, means providing in said cabinet a plurality of separate compartments for storage, means providing another compartment in said cabinet adapted to contain a supply of moisture, means 45 providing direct communication between said moisture compartment and each of said storage compartments, and means substantially preventing direct communication from any of said storage compartments to any other thereof.

50 3. A tobacco humidor of the character described comprising, in combination, a cabinet, means providing in said cabinet a plurality of separate compartments for storage, means providing another compartment in said cabinet adapted to contain a supply of moisture, means 55 providing direct communication between said moisture compartment and each of said storage compartments, means substantially preventing direct communication from any of said storage 60 compartments to any other thereof, said moisture compartment forming one wall of said cabinet and being removable from said cabinet to facilitate replenishment of the supply of moisture therein, and means releasably securing said 65 moisture compartment to said cabinet.

4. A tobacco humidor of the character described comprising, in combination, a cabinet, means providing a plurality of compartments vertically arranged in said cabinet and adapted 70 to receive material for storage, means providing for separate access to each of said compartments, means providing another compartment in said cabinet positioned to extend substantially from the bottom to the top thereof and adapted to 75 receive a quantity of absorbent material capable

of retaining a supply of moisture, means providing passages for direct communication between said moisture compartment and each of said storage compartments, and means substantially preventing communication between said storage compartments except through said moisture compartment.

5. A tobacco humidor of the character described comprising, in combination, a cabinet, a plurality of drawers for the reception of material for storage, means supporting said drawers one above the other in said cabinet for independent removal at the front of the cabinet, said supporting means engaging the bottoms of said drawers and cooperating therewith to effect substantial prevention of direct communication between adjacent drawers along the sides and the top thereof, means providing at the back of said cabinet a compartment adapted to contain a supply of moisture, and means providing direct communication between said moisture compartment and each of said drawers.

6. A tobacco humidor of the character described comprising, in combination, a cabinet, a plurality of drawers for the reception of material for storage, means supporting said drawers one above the other in said cabinet for independent removal at the front of the cabinet, said supporting means engaging the bottoms of said drawers and cooperating therewith to effect substantial prevention of direct communication between adjacent drawers along the sides and the top thereof, means providing at the back of said cabinet a compartment adapted to contain a supply of moisture, said moisture compartment extending substantially from the bottom to the top of said cabinet, and means providing coincident apertures in the inner wall of said compartment and the inner end of each of said drawers providing ready access for moisture from said compartment to said drawers.

7. A tobacco humidor of the character described comprising, in combination, a cabinet, a plurality of drawers for the reception of material for storage, means supporting said drawers one above the other in said cabinet for independent removal at the front of the cabinet, said supporting means engaging the bottoms of said drawers and cooperating therewith to effect substantial prevention of direct communication between adjacent drawers along the sides and the top thereof, means providing at the back of said cabinet a compartment adapted to contain a supply of moisture, said compartment extending

substantially from the bottom to the top of said cabinet, the inner end of each of said drawers terminating short of the bottom of the adjacent higher drawer leaving an opening therebetween, said drawers being adapted when closed to abut the inner wall of said moisture compartment to prevent circulation of air from drawer to drawer through said openings, and means providing in said inner compartment wall a series of apertures adapted to register with said openings and providing ready access for moisture from said compartment to said drawers.

8. A tobacco humidor of the character described comprising, in combination, a cabinet, a plurality of drawers for the reception of material for storage, means supporting said drawers one above the other in said cabinet for independent removal at the front of the cabinet, said supporting means engaging the bottoms of said drawers and cooperating therewith to effect substantial prevention of direct communication between adjacent drawers along the sides and the top thereof, means including inner and outer walls defining a compartment for containing a quantity of absorbent material adapted to receive and hold a supply of moisture, said compartment means being positioned at the rear of said cabinet and extending substantially from the bottom to the top thereof to form the rear wall of the cabinet, means releasably securing said compartment means to said cabinet, the inner end of each of said drawers terminating short of the bottom of the adjacent higher drawer leaving an opening therebetween, said drawers being adapted when closed to abut said inner wall of said moisture compartment to prevent circulation of air from drawer to drawer through said openings, and means providing in said inner compartment wall a series of apertures adapted to register with said openings and providing ready access for moisture from said compartment to said drawers.
